UNITED STATES PATENT OFFICE

ALVIN C. McCORD, OF CHICAGO, ILLINOIS

LUGGAGE UNLOADER FOR RAILWAY CARS

Application filed December 15, 1927. Serial No. 240,093.

This invention relates to luggage unloading means for railway passenger cars and more particularly Pullman cars.

The practice heretofore has been for the porter or attendant of the car to pile up all the hand luggage of the passengers in the vestibule of the car just before the train reaches its destination or unloading point. When the car carries a large number of passengers, as is usually the case on through fast trains, the luggage piled up in the vestibule occupies so much space that the luggage must be unloaded first at the destination before the passengers can alight from the train. This requires that the passengers wait in line in the aisle of the car until the porter can pass the luggage to the station porters who meet the train, and, when the vestibule is cleared of the luggage, then the porter opens up the trap and the passengers can leave the car. All this consumes some time and causes great annoyance to the passengers as it prevents their immediate exit from the car as soon as the train comes to a stop for unloading.

The object of my invention is to provide a luggage unloading means which may be installed in the vestibules of the cars as part of the regular equipment and permit all the luggage for a car to be rapidly and conveniently unloaded en masse from the vestibule as soon as the train stops, and thus allow the passengers to make immediate exit from the car without being delayed by the unloading of piled up luggage as heretofore.

Another object of my invention is to so construct and arrange the unloading mechanism that it may be shifted to either side of the car so that the luggage may be quickly and easily unloaded from either side as may be required by the position of the unloading platform.

A further object of my invention is to provide a collapsible container or carrier into which the luggage is placed by the porter so that the carrier may be collapsed into a relatively small compact form and be stored away when not used.

A further object of my invention is to provide the unloading mechanism with a crane so that the container holding the luggage

may be readily swung out of the vestibule clear of the car and be deposited on the unloading platform from either side.

A further object of my invention is to provide a trackway which is mounted in the vestibule high enough not to interfere with the free passage through the vestibule yet permit the crane to be readily shifted from side to side of the car so that it may be swung out of the vestibule of the car to carry the loaded container to the particular side of the car at the unloading platform.

The invention consists further in the matters hereinafter described and claimed.

In the accompanying drawings—

Fig. 1 is a vertical sectional view through the vestibule of a Pullman car and showing installed therein the luggage unloading means of my invention, the section being taken on line 1—1 of Fig. 2;

Fig. 2 is a horizontal sectional view taken on line 2—2 of Fig. 1;

Figs. 3 and 4 are vertical sectional views showing details of construction, taken on lines 3—3 and 4—4, respectively, of Fig. 1; and

Fig. 5 is a horizontal sectional view also showing a detail of construction and taken on line 5—5 of Fig. 1.

In the drawings, 1 indicates the vestibule of a railway car, and 2 the wall structure between the body of the car and the vestibule. Said wall 2 has the usual door opening 3 by means of which entrance and exit may be had into and out of the body of the car from the vestibule, as in car design.

4 indicates generally the front wall of the vestibule, and 5, 6 indicate the door openings of the vestibule on opposite sides of the car, 7, 8 indicate the doors of the vestibule for the openings 5, 6, and these doors, as in car design, are hinged to the wall structure 2 and swing in the vestibule against and away from upright columns 8, 8 in the front wall structure 4 in the closing and opening of said doors. These doors at their lower edges swing over hinged trap doors 9, 9, which when in closed or lowered position extend over the steps 10, 10 of the car and form a continuation of the floor or platform 11 of the vestibule in front of the door opening 3, as usual.

Arranged in the vestibule just inside of its front wall 4 and extending from one column 8 to the other is a track member 12 of my improved luggage unloading means. The track member 12 is rigidly secured in place near the top of the vestibule in horizontal position and in general alignment with the upper ends of the door openings 5, 6 of the vestibule, as shown in Fig. 1. This positions the track member 12 high enough in the vestibule so as not to interfere with the free passage through the vestibule from one car to another. The track member 12 is preferably made in the form of a hollow housing in which is located a traveling carriage 13. This carriage in the form shown in the drawings is provided with two pairs of rollers 14, 14 a pair at each end of the carriage, and which rollers roll on inwardly extending flanges 15, 15 along the bottom of the trackway 12. The carriage 13 has a depending hanger 16 which extends below the carriage through a slot provided between the opposed inner edges of the track flanges 15, 15, as shown in Fig. 3.

Arranged below the track member 12 is a crane 17, preferably of I-beam section and having a horizontal arm or boom 18 and a vertical arm 19. The crane 17 is carried by the roller carriage 13 so that the crane may be shifted from one end of the trackway to the other for the purpose to be presently described. The crane 17 is suspended from the roller carriage 13 through the medium of a clamp 20 which engages about the upper flange of the I-beam section of the horizontal arm or boom 18 and which clamp has a swivel connection with the lower end of the hanger 16 of the carriage, as indicated in Fig. 3. This swivel connection may be made in any desired manner, one way being illustrated generally in Fig. 3. This construction includes opposed circular portions 21, 22 on the hanger 16 and clamp 20, respectively, and an axis member 23 extending downward from the hanger 16 through the center of the circular portion 22 of the clamp and having its lower end secured thereto by a nut or otherwise. To permit the clamp and its crane to turn easily with respect to the hanger 16, ball bearings 24 are located between the circular portions 21, 22 in grooves or raceways provided in said portions for the balls.

Arranged to travel on the lower horizontal flange of the boom or arm 18 are a pair of rollers 25, 25 which are carried by a yoke 26 which straddles the under side of the arm 18 and from which depends a hanger 27 carrying a hoisting device which may be in the form of a chain block 28. The hanger 27 has a swivel connection with the yoke 26 so that the hanger and its hoisting device may be readily turned with respect to the yoke. The raising and lowering chains 29, 30 of the block carry a hook 31 adapted to engage a pair of bails 32, 32 which are at the upper end of a

collapsible luggage receiving container or receptacle 33. The latter is made so that it can be readily collapsed into a relatively flat compact form and thus be stored away when not in use. A number of brackets (not shown) may be provided in the vestibule to receive and support the collapsed container when it is not in service.

The container 33 is provided at its lower end with a number of casters or other rollers 34 so that the container, either when loaded or empty, may be readily moved back and forth over the platform 11 and the traps 9, 9 of the vestibule. The container is held in a distended or set up position by suitable locking links 35 at the opposite sides of the container, as shown in Fig. 1.

The crane 17 has the lower end of its vertical arm 19 formed to provide a trunnion 36 which is adapted to be clamped in either one of a pair of split bearings 37 which are located at the opposite sides of the vestibule and carried by suitable brackets 38 secured to the wall structure 4 just inside of the columns 8, 8, as shown in Figs. 1 and 5. The hinged member 39 of each split bearing is held in closed position about the trunnion 36 when the latter is in the bearing by a removable locking pin 40 which is inserted through registering holes in ears 41, 42 carried on the hinged member of the bearing and the bracket 38, respectively, as shown in Fig. 1.

The mechanism shown and described is operated as follows: The porter or attendant distends the container 33 and locks it in its distended form by the locking links 35, 35. At this time the container is not engaged with the hook 31 so that it may be moved over the floor of the vestibule into any position most convenient for loading it with the hand luggage of the passengers of the car. The loaded container 33 may be shoved to one side of the vestibule so as to be out of the way of the door opening 3 and the other passage of the vestibule which leads to the next adjacent car. As the train pulls into the terminal or station, the porter notes on which side of the car the unloading platform is located and opens the door 7 of the vestibule on that side of the car when the train comes to a stop. If the crane 17 is on that side of the vestibule, the porter shoves the loaded container 33 under the crane and then engages the bails 32, 32 with the hook 31 of the chain block, and, by manipulating the chain block, hoists the loaded container free of the floor of the vestibule. He then pushes the loaded container out of the vestibule through the open doorway, the crane turning on its pivots (aligned swivel and trunnion 36) and its boom or arm 18 passing outward through the doorway and carrying the loaded container therewith, as shown in dotted lines in Fig. 2. If the container in this movement is not completely free of the vestibule, the container is pushed

to the outer end of the boom 18, whereupon the loaded container is lowered to the station platform by the porter manipulating the chain block 28. The station porter moves the loaded container to one side of the steps of the car, whereupon the car porter opens the trap 9 and the passengers alight from the car, all within a few seconds after the train has stopped with no piled up baggage or luggage 10 to interfere with or delay their exit from the car as heretofore.

Should the crane 17 be on the side of the car opposite the unloading platform when the train pulls in, the porter will, after opening the door 7 of the vestibule on the side of the unloading platform, release the lower end of the crane from the split bearings 38, 39, at the side of the car opposite the unloading platform and then shift the entire crane to 20 the unloading side of the car through the medium of the roller carriage 13 and the trackway 12. When the crane reaches the unloading side of the car, the porter then clamps the trunnion end 36 of the crane in 25 the split bearings at that side of the car so that the crane may be swung beyond the side of the car and permit the loaded container 33 to be lowered to the station platform as heretofore described. After locking the 30 trunnion end 36 of the crane in the bearing, the porter will lock the roller carriage 13 against movement in the trackway by a pin 43, which is insertable through openings 44 in the track housing and the hanger 16, respectively, as shown. The track housing 12 is provided with two of these openings, one adjacent each end of the housing 12 so that the roller carriage may be locked against accidental movement at either end of the track- 40 way.

By reason of the mechanism shown and described, the hand luggage of passengers of the car may be unloaded en masse from the vestibule of the car with ease and dispatch and within a few seconds after the train has arrived at its destination so that the passengers are not delayed in the aisle of the car awaiting the unloading of the luggage as heretofore. This is a decided advantage in connection with unloading of the car because the container 33 provides a receptacle to receive and hold the luggage, and the crane 17 and the rest of the mechanism permit the loaded container to be readily swung out of the vestibule of the car and lowered to the station platform in a very short time, so that unloading of the car may be quickly accomplished immediately that the train has arrived at the terminal. A 50 mechanism of my invention will be installed in each of the two vestibules of the car, so that the car may be quickly unloaded at either end. It will be observed that all of the operative mechanism of the device is located be- 55 low the upper surface of the track way or

main support 12, thereby allowing said support to be located close to the top of the vestibule.

The details of structure and arrangement of parts shown and described may be variously changed and modified without departing from the spirit and scope of my invention. 70

I claim as my invention:

1. The combination with the vestibule of a railway car, of a container for hand luggage, a trackway in the vestibule and extending from side to side thereof, a crane supported by said trackway and shiftable along the same to either side of the vestibule, said crane having a vertical arm and a horizontal arm, means fixed in the vestibule at the opposite sides thereof and providing a pivotal support for the vertical arm whereby the horizontal arm may be swung into and out of the vestibule to either side of the car, and a hoisting device carried by the horizontal arm whereby the container may be lowered from the vestibule at either side of the car. 80

2. The combination with the vestibule of a railway car, of a container for hand luggage, a trackway mounted in the vestibule and extending from side to side thereof, a crane having a vertical arm and a horizontal arm, a roller carriage provided on the trackway and having a swivel connection with the horizontal arm whereby the crane may be shifted along the trackway to either side of the vestibule and the horizontal arm be swung into and out of the vestibule at either side of the car, split bearings fixed in the vestibule at opposite sides thereof to provide a pivotal support for the lower end of the vertical arm at either side of the vestibule, and a hoisting device carried by the horizontal arm whereby the container may be lowered from the vestibule at either side of the car. 90

3. The combination with a railway car, of a container for luggage, a track way within the car and extending across the same from one side thereof to the other, a carrier shiftable along said track way, an arm pivotally connected with said carrier whereby the arm may be swung into and out of the car when at either end of said trackway, and a hoisting device carried by said arm whereby the container may be swung out of the car on said arm and be lowered for loading or unloading. 100

In testimony whereof I affix my signature.

ALVIN C. McCORD.
